UNITED STATES PATENT OFFICE.

GEORGE W. DICKERSON, OF GALION, OHIO, ASSIGNOR TO THE NORTH ELECTRIC MANUFACTURING COMPANY, OF GALION, OHIO, A CORPORATION OF OHIO.

TELEPHONE-SWITCH.

1,374,366.

Specification of Letters Patent. Patented Apr. 12, 1921.

Application filed June 26, 1916. Serial No. 105,781.

To all whom it may concern:

Be it known that I, GEORGE W. DICKERSON, a citizen of the United States, residing at Galion, in the county of Crawford and State of Ohio, have invented certain new and useful Improvements in Telephone-Switches, of which the following is a specification.

My invention relates to electrical switches and is especially designed to be used in connection with telephone exchange systems or other systems wherein it is desirable to interconnect a large number of electrical circuits.

15 This switch is particularly adapted to be used as a line selecting switch for quickly and automatically effecting connections with calling subscribers' lines in telephone exchange systems.

20 The switch is preferably arranged to serve a group of one-hundred lines. The lines are formed into sub-groups of ten lines each and connected to ten parallel rows of flexible contact springs.

25 The movement of the springs of each row is controlled by an associated electro-magnet. The springs of each row are arranged in sets, one set being allotted to each line. In the present instance I have shown three 30 springs in pairs as comprising a set. As there are ten lines served by each row there will be thirty pairs of contact springs to each row.

35 Intersecting or crossing the tens rows of flexible springs at right angles are ten sets of units contacts. Each set of these contacts comprises three metallic strips, provided respectively with ten downwardly projecting extensions.

40 These extensions are normally out of engagement with the tens contact springs. Each row of units contacts is provided with an electro-magnet for controlling its movement. In order to connect with any line it is only necessary to operate the electro-magnet associated with the tens row containing the desired contact. The operation of this electro-magnet will bring the sets of contacts of the row into alinement with the extensions of all the units strips. Then by operating the electro-magnet of the strip which is in alinement with the contacts of the desired line, the extensions of this operated strip will come into engagement with 55 the contacts of the desired line.

The details of construction and operation will be pointed out in the description to follow.

My invention is illustrated in the accompanying drawings wherein:

Figure 1 is a plan view of the switch.

Fig. 2 is a side view of the switch.

Fig. 3 is a rear view of the switch.

Fig. 4 is the side sectional view on line a—a of Fig. 1.

Fig. 5 is a side sectional view on line b—b of Fig. 1.

Fig. 6 shows a side view of a units element in detail.

Fig. 7 shows a plan view of a units element.

Fig. 8 shows a plan view of the tens element with a number of the line or group contacts removed.

Fig. 9 is an enlarged sectional view showing a portion of a tens element.

Fig. 10 is a schematic arrangement showing the manner of coöperation of the tens and units elements.

Referring to the drawings, the various magnets and moving parts are mounted and supported within a main frame or case 50. The tens magnets 40 are mounted on opposite sides of this case, five being on one side and five on the other. The units magnets 50 are mounted in a similar manner on opposite sides of the case. The magnets are held in place by the screws 45. Each tens magnet 40 is provided with an L shaped armature 42, plainly shown in Figs. 2 and 5. An opening is provided in the frame 50 to allow the armature to be mounted so the smaller arm can be engaged or attracted by the core of electro-magnet 40. Each armature is held in place by means of a leaf spring 43 which bears against the longer side of the armature, as shown in Figs. 2 and 5.

By referring to Fig. 2, it will be noted that the opening in the frame is cut in such a manner to provide a series of lips or projections 46 which pass through the cut-out portions 48 of the armatures. Extending across the four sides of the frame are bars or strips 44 which are fastened to the frame by means of the screws 47. These bars pass just below the bottom portion of the armatures as shown in Figs. 2, 3 and 4, and serve to securely hold them in position. There is, however, sufficient space between the bars

44 and the armatures to allow free movement of the latter.

Each armature 42 is arranged to operate a rod or arm. These rods are preferably made of square stock, as shown at 26, which is rounded or reduced as shown at 25 and 35. The portion 25 is provided with a thread which engages a threaded opening in the metallic bushing 23 embedded or 10 molded in the insulated bar 20, as shown in Fig. 7.

The bar 20 is provided at its opposite end with a metallic bushing 28 which has a threaded opening adapted to receive the 15 rod 29.

The rods 29 and the rounded portions 25 serve to support the bars 20 and pass through the brackets 36 mounted on top of the frame 50.

20 The bar or rod 26 is also provided with an adjusting nut 27. By rotating this nut the threaded portion turns within the bushing 23. In order to hold the threaded portion in its adjusted position a lock nut 24 is provided. The tens bar 20 which is of insulating material is provided with a series of openings 21 through which the contact springs 22 pass. These contact springs are bowed as shown in Fig. 9 and provided with 30 the flared ends 33 which project above the bar 20. There are thirty openings 21 in the bar 20 to accommodate thirty pairs of springs 22. The opposite ends of the springs 22 are rigidly fastened in a bed of insulating material 30, as plainly shown in Figs. 5 and 9. These contacts 22 project beyond or beneath the bed 31 so as to form terminals to which electrical conductors may be connected. The thirty pair of contacts 22 for 40 each tens bar 20 are arranged in groups of ten, there being three pairs of contacts to each set.

Referring to Figs. 4, 6 and 7, the details of construction and manner of operation of 45 the units bars or contacts are shown. The units bars are provided with similar rods 9 of square material which are rounded and reduced at 7 and 12. The reduced portion 7 is threaded and engages a metallic bushing 50 6 embedded or molded within the plug of insulating material 4. Each unit bar is composed of three metallic strips 1, 2, 3, provided with ten extensions 11. These extensions project downwardly and are adapted 55 to engage the flexible contacts 22. The metallic strips 1, 2 and 3 are molded or embedded in the insulating blocks 4 and 5 as shown in Fig. 7.

The insulating block 5 is also provided 60 with a metallic bushing 14 into which a rod 15 is threaded. The rods 15 and the reduced portions 7 serve to support the units bars and pass through the brackets 37 mounted on top of the frame 50.

As shown in the drawings the tens bars or 65 sets of contacts are below the units bars. The extensions 11 of the units bars, however, project downwardly so as to slide between the flared ends 33 of the pairs of springs 22. 70

Under normal conditions the extensions 11 rest in position out of line with the ends 33 as shown in Figs. 2 and 4. In other words the extensions do not interfere with the free movement of the tens bars or contact 75 springs.

By referring particularly to Figs. 5, 7 and 9, it will be seen that when a magnet 40 is operated or energized it will attract its armature and the longer end will bear 80 against the adjusting nut 27 and cause the bar 20 to move and cause a consequent movement of the thirty paired contacts 22. When the magnet 40 is deenergized the bar and contact springs will assume their normal 85 position, due to the tension exerted by the spring 43 and also due to the tension under which the springs 22 are normally adjusted.

As there are ten units bars each comprising ten sets of contacts, it follows that for a 90 full equipment there will be ten sets of units bars as shown in Fig. 7.

Referring to Fig. 1, it will be noted that by energizing a particular magnet 40 a tens bar controlling the movement of ten sets of 95 contact springs 22 will be operated and cause the flared ends 33 to come in alignment with the projections 11 of the ten units bars. No. 1 set of three paired contacts will be in alignment with the extensions 11 of 100 No. 1 units bar. No. 2 set of contacts in alignment with the extensions 11 of the No. 2 units bar, etc.

In order to select or interconnect with any one of the sets of ten contacts it will only be 105 necessary to energize the proper units magnet 50 to cause the projections 11 to engage the flared ends 33 of a set of springs 22.

In the foregoing it will be seen that one-hundred combinations or interconnections 110 can be effected. In order to select a particular set of tens contacts it is only necessary to operate the particular tens bar containing the desired set of contacts and then to operate the particular units bar to engage 115 the desired set of contacts.

As shown in Figs. 1, 2 and 3, the case 50 is made of one piece of metal, stamped to assume the proper form.

For purpose of illustration I have shown 120 the switch adapted to the circuits of the type shown in Fig. 10.

A set of contacts 22 are allotted to each line. Each set comprising three pairs of springs or contacts are connected in the manner shown. 125

The units contacts 1, 2, 3, of each set are connected in multiple; that is to say, No. 1

strip of each of the rows are connected together and likewise strips 2 and 3 of each row are connected together.

The contacts 1, 2 and 3 are shown connected to a cord circuit of the standard type.

It will be noted that the substation 110 comprising the usual receiver transmitter and ringer is connected to the line conductors which extend to the line relay 112 and to ground through the contacts of the cutoff relay 111.

The removal of the receiver closes the circuit of relay 112 thereby lighting the signal lamp 113. The lighting of this lamp indicates the number of the particular calling line. In order to connect the calling line to the cord circuit the button 116 is depressed thereby completing the circuit of the electromagnet 40. The operation of this magnet causes the associated row of contacts 22 to be brought into alignment with the row of contacts 1, 2, 3.

By pressing the button 115 the electromagnet 50 is operated and brings contacts 1, 2, 3 into engagement with the set of contacts associated with the calling line. As soon as this connection is effected relays 102 and 111 are placed in series. The operation 30 of relay 111 disconnects the line relay 112 thereby extinguishing the signal lamp 113.

Talking current is supplied to the calling subscriber at 110 through the winding of relay 100 and the winding of coil 101.

35 The connection is completed to a called line or trunk by placing the plug into the jack 107.

At the termination of the conversation the calling subscriber upon replacing his receiver causes the restoration of relay 100. This relay in restoring completes the circuit of the supervisory lamp 103 indicating that the line should be disengaged, whereupon the plug 106 is removed from the 40 jack 107 and the buttons 115 and 116 restored to their normal position. The restoration of these buttons causes the de-energization of magnets 40 and 50 thereby causing the switch contacts to resume their 45 normal position.

50 While I have shown the magnets 40 and 50 operated by buttons 115 and 116 they can be automatically operated upon the removal of the receiver at the calling sub-station in a manner similar to the operation of the tens and units relays shown in the following 55 patents to E. E. Clement: 1,105,490 of July 28, 1914; 939,188 of Nov. 2, 1909; 1,107,146 of August 11, 1914; 1,107,152 of August 11, 60 1914 and 1,109,617 of September 1, 1914.

The tens magnets 40 and the units magnets 50 can be substituted for the tens and units relays of the foregoing patents.

65 The contacts controlled by the tens and units magnets 40 and 50 when a plurality

of sets are used are connected in the same manner as the contacts of the tens and units relays of different groups or sets.

While I have shown a switch provided with ten rows of tens contacts and ten rows of units contacts, the number can be increased to serve a large number of lines or trunks or diminished to serve a smaller number.

The switch as designed forms a compact 75 structure with a minimum number of parts and wiring. All the parts are readily accessible and capable of quick and accurate adjustment.

While I have used the term "telephone 80 switch" in the claims, it is to be understood that the switch is not limited to such use but may be used for purposes of connecting any form of electrical circuits.

Having thus described my invention what 85 I desire to secure by Letters Patent is:

1. In a telephone switch, a plurality of sets of contacts arranged in a row independent of one another, each set of contacts comprising a plurality of flexible springs, 90 a plurality of other contacts arranged in rows, means for operating a row of individual flexible contacts, and means for operating the second mentioned contacts for coöperating with an individual set of flexible contacts independent of the other contacts in the row.

2. In a telephone switch, a plurality of rows of contacts, each row comprising a set of flexible springs independent of one another, a plurality of other rows of contacts arranged at right angles to the first mentioned rows, means for causing the coöperation between said contacts by first operating a row of flexible springs and thereafter 100 105 operating a row of the second mentioned contacts.

3. In a telephone switch, a plurality of rows of contacts, each row comprising a plurality of sets of flexible contact springs 110 independent of one another, a plurality of coöperating contacts arranged at right angles to said rows, means comprising an electro-magnet for operating a row of flexible contacts, and means comprising an 115 electro-magnet for operating the coöperating contacts to engage a particular set of flexible contacts, said electro-magnets being the sole means for causing the engagement of said contacts.

4. In a telephone switch, a row of flexible contacts, an electro-magnet common to and for operating said row of contacts, a plurality of sets of coöperating contacts arranged at right angles to said row, an electro-magnet for operating said coöperating contacts, means for operating both of said electro-magnets for causing the engagement of a particular set of flexible contacts with 125 said coöperating contacts, said electro-mag- 130

nets being the sole means for causing the engagement of said contacts.

5. In a telephone switch, a plurality of flexible contacts arranged in a row, said contacts being rigidly fastened at one end, an insulated element, the free ends of said contacts passing through said insulated element, a plurality of coöperating contacts, means comprising an electromagnet for 10 operating said element in order to bring the free ends of said springs into alinement with said coöperating contacts.

6. In a telephone switch, the combination of a plurality of sets of flexible contacts arranged in a row independent of one another, said contacts arranged in pairs, a movable element, the free ends of said contacts passing through said movable element, a plurality of coöperating contacts, means 15 20 for first operating said elements to move said flexible contacts into alinement with said coöperating contacts, and means for operating said coöperating contacts to engage with the flexible contacts with which 25 they are alined.

7. In a telephone switch, a plurality of flexible contacts arranged in a row, one end of each of said contacts being rigidly fastened, a movable element, the free end of 30 each of said contacts passing through said movable element, a plurality of sets of coöperating contacts, means comprising an electromagnet for operating said element to bring said flexible contacts into alinement 35 with said coöperating contacts, and means comprising an electromagnet for operating said coöperating contacts to engage said flexible contacts.

8. In a telephone switch, a row of contacts comprising a plurality of sets of flexible contacts independent of one another, a plurality of rows of secondary contacts, means for operating said row of flexible contacts whereby all of said sets are brought 40 45 into alinement with all the rows of secondary contacts at the same time, and means for operating any one of said rows of secondary contacts for engaging the particular set of flexible contacts with which it is alined, the operation of said rows being in a longitudinal direction only.

9. In a telephone switch, the combination with a plurality of sets of flexible contacts arranged in a row, a movable element, the 50 55 free ends of said contacts passing through said movable element, a plurality of secondary contacts, means for operating said element to move said flexible contacts into alinement with said secondary contacts, and 60 means for operating a particular secondary contact for engaging the flexible contact with which it is alined.

10. In a telephone switch, a plurality of sets of flexible contacts arranged in a row, 65 one end of each of said contacts being rig-

idly fastened, a movable element, the free end of each of said contacts passing through said movable element, a plurality of sets of secondary contacts, means for operating said element to bring said flexible contacts 70 into alinement with said secondary contacts, and means for operating any one of said sets of secondary contacts to engage the said set of flexible contacts with which it is alined.

75

11. In a telephone switch, a plurality of rows of contacts, each row comprising a plurality of sets of flexible contacts independent of one another, a plurality of rows of secondary contacts, means for operating 80 a particular row of flexible contacts whereby each set of said row is brought into alinement with a particular row of secondary contacts, and means for operating any row of secondary contacts to engage the set of 85 flexible contacts with which it is alined, the operation of said rows being in a longitudinal direction only.

90

12. In a telephone switch, the combination of a plurality of sets of primary contacts arranged in a row independent of one another, a plurality of rows of secondary contacts, each row of said secondary contacts being allotted to a particular set of primary contacts, means for operating the 95 row of primary contacts for bringing each individual set into alinement with its allotted row of secondary contacts, and means for operating a row of secondary contacts for engaging the set of primary contacts 100 with which it is alined, the operation of said rows being in a longitudinal direction only.

100

13. In a telephone switch, the combination of a plurality of rows of primary contacts, each row comprising a plurality of sets of contacts independent of one another, a plurality of rows of secondary contacts, each of said rows of secondary contacts having access to a particular set of individual primary contacts of each row, means for operating any row of said primary contacts whereby each set of the row is brought into alinement at the same time with a row of 105 secondary contacts, means for operating any 110 row of secondary contacts for engaging the set of primary contacts with which it is alined, the operation of said rows being in a longitudinal direction only.

115

14. In a telephone switch, the combination of a plurality of rows of primary contacts, each row comprising a plurality of sets of contact springs fastened at one end independent of one another, a plurality of rows of secondary contacts extending at 120 right angles to the rows of primary contacts and adapted to engage the free ends thereof, each row of secondary contacts arranged to have access to a particular set of primary contacts of each row, means for operating 130

- said primary contacts whereby the free ends of each set of the row is brought into alinement at the same time with a row of secondary contacts, means for operating any 65
- 5 row of secondary contacts for engaging the set of primary contacts with which it is alined, the operation of said rows being in a longitudinal direction only.
15. In a telephone switch, the combination of a bank of primary contacts arranged in rows, each row comprising a plurality of sets of contacts independent of one another, a plurality of rows of secondary contacts provided with downwardly extending projections for engaging the primary contacts, each row of secondary contacts having access to a particular set of individual primary contacts of each row, means for operating a row of said primary contacts where- 70
- 10 by each individual set is brought into alinement at the same time with the rows of secondary contacts to which it has access, means for operating any row of secondary contacts for causing the downwardly projecting extensions to engage the particular set of primary contacts with which it is alined, the operation of said rows being in a longitudinal direction only.
15. In a telephone switch, the combination with a plurality of flexible contacts arranged in a row, a movable adjustable element, said contacts passing through said movable adjustable element, a plurality of coöperating contacts provided with a com- 75
- 20 mon adjusting device, means for operating said element to move said flexible contacts into alinement with said coöperating contacts, and means for operating said coöperating contacts to engage said flexible contacts.
25. In a telephone switch, the combination with a plurality of contacts mounted within a single unit structure, certain of said contacts comprising a number of rows 80
- 30 of flexible primary contacts, other of said contacts comprising a plurality of rows of secondary contacts, a magnet mounted upon said unit structure individual to each of said rows of contacts, means for operating said magnets for causing the primary and secondary contacts to cooperate, said magnets serving as the sole means for causing the coöperation of said contacts.
35. In a telephone switch, the combination with a bank of contacts mounted within a frame, said contacts comprising a plurality of rows of flexible contacts, each of said rows being provided with an adjustable movable element, a plurality of rows 85
- 40 of secondary contacts mounted upon said frame, each row of flexible contacts and each row of secondary contacts being pro- 90
- 45 vided with a magnet mounted upon said frame, means for operating said magnets
- 50 for causing the coöperation of the flexible and secondary contacts, said magnets serving as the sole means for causing the coöperation of said contacts.
19. In a telephone switch the combination of a plurality of sets of flexible contacts arranged in a row independent of one another, said contacts arranged in pairs, a movable element, the free ends of said contacts passing through said movable element, a plurality of coöperating contacts, means for moving said element to bring said flexible contacts into alinement with said coöperating contacts, and means for operating said coöperating contacts to cause them to form a wiping contact between said pairs 95
- 55 of flexible contacts.
20. In a telephone switch, the combination of a plurality of line contacts, arranged in a row, said contacts arranged in sets, each set being allotted to an individual line, a magnet common to said row, a row of secondary contacts for each set of line contacts, a magnet for each row of contacts, means for operating the magnet of the row of line contacts for bringing each set of individual contacts into alinement at the same time with a row of secondary contacts, means for operating any magnet of a secondary row 100
- 60 for causing the contacts thereof to effect engagement with the set of individual contacts with which it is alined.
21. In a telephone switch, a row of primary contacts, an electromagnet common to and for operating said row of contacts, a plurality of sets of secondary contacts 105
- 65 arranged at right angles to said row, an electromagnet for operating said secondary contacts, means for causing the engagement of a particular set of primary contacts with said secondary contacts, means for energizing said electromagnets, a single energization of said electromagnets serving to cause the engagement of said contacts.
22. In a telephone switch, a plurality of primary contacts arranged in a row, one end of each of said contacts being rigidly fastened, a movable element, the free end of each of said contacts being controlled by said movable element, a plurality of sets of secondary contacts, means comprising an 110
- 70 electromagnet for operating said movable element to bring said primary contacts into alinement with said secondary contacts, and means comprising an electromagnet for operating said secondary contacts to engage 115
- 75 said primary contacts, said magnets being the sole means for causing the engagement of said contacts.
23. In a telephone switch, the combination of a plurality of sets of primary contacts arranged in a row, a movable element, said element controlling the movement of said primary contacts, a plurality of second- 120
- 80
- 85
- 90
- 95
- 100
- 105
- 110
- 115
- 120
- 125

ary contacts, means for operating said movable element to move said primary contacts into alinement with said secondary contacts, and means for operating a particular secondary contact for engaging the primary contact with which it is alined.

24. In a telephone switch, the combination of a plurality of contacts mounted within a single unit structure, certain of 10 said contacts comprising a plurality of rows of primary contacts, other of said contacts comprising a plurality of rows of secondary contacts, a magnet individual to each row of contacts, means for operating said 15 magnets for causing primary and secondary contacts to coöperate, said magnets serving as the sole means for said coöperation.

25. In a telephone switch, a plurality of rows of primary contacts, each row comprising 20 a set of springs independent of one another, a plurality of rows of secondary contacts arranged at right angles to the first mentioned rows, means for causing the coöperation between any number of said 25 primary and secondary contacts by operating a plurality of rows of primary contacts and thereafter operating a plurality of rows of secondary contacts.

26. In a telephone switch, a plurality of 30 rows of primary contacts, each row comprising a plurality of sets of contact springs independent of one another, a plurality of rows of secondary contacts arranged at 35 right angles to the rows of primary contacts, a magnet individual to each row of contacts, means for operating any number of said magnets for causing the coöperation of any number of primary and secondary contacts, said electromagnets being the sole 40 means for causing the said coöperation.

27. In a telephone switch, a plurality of sets of primary contacts arranged in a row independent of one another, a plurality of rows of secondary contacts, means for causing 45 the coöperation of a plurality of primary and secondary sets of contacts by first operating the row of primary contacts and

then operating the required number of rows of secondary contacts.

28. In a telephone switch, a plurality of 50 rows of primary contacts, each row comprising a plurality of sets of contacts independent of one another, a plurality of rows of secondary contacts, means for operating any number of rows of primary contacts 55 whereby a set of each row is brought into alinement with the rows of secondary contacts, and means for operating any number of rows of secondary contacts so as to cause the coöperation of contacts with which they 60 are alined, the operation of said rows being in a longitudinal direction only.

29. In a telephone switch, the combination of a plurality of rows of primary contacts, each row comprising a plurality of 65 sets of contacts independent of one another, a plurality of rows of secondary contacts, each row of secondary contacts having access to a particular set of individual primary contacts of each row, means for operating any number of rows of primary contacts whereby each set of the row is brought into alinement with a row of secondary contacts, means for operating any number of rows of secondary contacts for engaging 70 the set of primary contacts of the row with which it is alined, the operation of said rows being in a longitudinal direction only.

30. In a telephone switch, a plurality of primary contacts, arranged in a row, an 80 electromagnet for said row of contacts, a plurality of secondary contacts, an electromagnet for said secondary contacts, means for energizing said electromagnets, a single energization of said electromagnets serving 85 to cause the coöperation of said primary and secondary contacts.

In testimony whereof I affix my signature in the presence of two witnesses.

GEORGE W. DICKERSON.
